Primary Examiner—Nelson C. Holtje

[57] CLAIM

The ornamental design for an optical lens vertex measuring projector, as shown and described.

DESCRIPTION

FIG. 1 is a front perspective view of an optical lens vertex measuring projector showing my new design;
 FIG. 2 is a left rear perspective view thereof;
 FIG. 3 is a right front perspective view thereof;
 FIG. 4 is a top front perspective view thereof.

FIG. 1**FIG. 2****FIG. 3**

FIG. 4
